UNITED STATES PATENT OFFICE.

WALTER LUTTRINGHAUS, OF MAYWOOD, ILLINOIS.

DESIGN FOR A BERLIN KETTLE.

53,309.

Specification for Design.

Patented May 13, 1919.

Application filed February 10, 1917. Serial No. 147,956. Term of patent 14 years.

To all whom it may concern:

Be it known that I, WALTER LUTTRINGHAUS, a citizen of the United States, residing at Maywood, in the county of Cook and State of Illinois, have invented a new, original, and ornamental Design for a Berlin Kettle, of which the following is a specification, reference being had to the accompanying drawing, forming a part thereof.

The figure is a perspective view of a Berlin kettle showing my new design.

I claim:

The ornamental design for a Berlin kettle as shown.

WALTER LUTTRINGHAUS.
